United States Patent Office

Des. 202,109
Patented Aug. 31, 1965

202,109

PORTABLE RADIO OR SIMILAR ARTICLE

Cornelius T. de Kam, Edgewood, Pa., assignor to Westinghouse Air Brake Company, Swissvale, Pa., a corporation of Pennsylvania

Filed May 26, 1964, Ser. No. 80,157

Term of patent 14 years

(Cl. D26—14)

Fig. 1.

Fig. 3.

Fig. 2.

Fig. 4.

FIG. 1 is a front perspective view of a portable radio or similar article showing my design;

FIG. 2 is a front elevational view, the rear being substantially a mirror image thereof;

FIG. 3 is a right side elevational view thereof; and FIG. 4 is a left side elevational view thereof.

As a matter of convenience portions of the drawing figures have been broken away.

The dominant features of my design are shown in full lines.

I claim:

The ornamental design for a portable radio or similar article, substantially as shown and described.
